UNITED STATES PATENT OFFICE.

CHARLES A. PATRICK, OF BELLAIRE, TEXAS.

PACKAGE-TIE.

1,089,952.

Specification of Letters Patent. Patented Mar. 10, 1914.

Application filed May 31, 1912. Serial No. 700,760.

To all whom it may concern:

Be it known that I, CHARLES A. PATRICK, a citizen of the United States, residing at Bellaire, in the county of Harris and State 5 of Texas, have invented new and useful Improvements in Package-Ties, of which the following is a specification.

This invention relates to the class of package ties and more specifically to those ties 10 which are designed for use by letter carriers for the purpose of holding a quantity of letters or newspapers.

An object of this invention is to provide a package tie which can be readily attached 15 to or detached from the package whenever occasion requires.

A still further object is to provide a package tie which is simple in construction and one which can be manufactured and placed 20 upon the market at a very small cost.

With the above and other objects in view, my invention consists in such details of construction and in the arrangement and combination of parts as will be hereinafter 25 more fully described and specifically pointed out in the appended claim.

In describing my invention in detail reference will be had to the accompanying drawings wherein like characters denote like 30 or corresponding parts throughout the several views, and in which:—

Figure 1 is a perspective view of my invention as applied to a package. Fig. 2 is a plan view of the same in an open position. 35 Fig. 3 is a fragmentary view, and Fig. 4 is a detailed view.

In the accompanying drawings wherein is illustrated the preferred form of my invention, the numeral 1 designates a quantity 40 of letters in connection with which my invention has been illustrated.

My invention includes the spring members 2, each of which is preferably formed from a single piece of wire, and which members have 45 formed at their extremities coils 3. Portions of the spring members are bent as shown at 4 whereby they may receive the ends of straps 5, 6, 7 and 8 respectively. Straps 5 and 6

are secured to one of the spring members while the others are secured to the other 50 spring member. Leaf springs 9 are pivoted upon each of the straps 5 and 6, the said leaf springs having a handle portion formed thereon and a lug depending therefrom. It is readily obvious that the leaf spring can 55 be easily manufactured by this arrangement. The lugs 11 project through apertures which are formed in the straps 5 and 6 serving the purpose which will be hereinafter set forth. The straps 5 and 6 are provided at 60 their extremities with guide arms 12 for the reception of the other straps 7 and 8, the said straps 7 and 8 being provided with spaced apart apertures 13 as shown. The said apertures are adapted to be engaged 65 by the lugs 11 thereby securely holding the package in place.

It is obvious that when my invention is in place as is clearly shown in Fig. 1 the package can be securely yet yieldingly held and 70 all danger of having the contents injured or defaced in any manner obviated.

I desire it to be understood that I may make slight changes in the construction and in the arrangement and combination of 75 parts provided such changes fall within the scope of the subjoined claim.

Having thus described my invention what I claim as new and desire to secure by Letters Patent is:

A package tie including a pair of springs substantially elliptical in an expanded position and provided with depressed portions at opposite points on the ellipse, straps engaging each of said depressed portions 85 whereby to prevent lateral movement of the same, adjustable interlocking means associated with said straps, and arms formed on the opposite ends of one of said straps for facilitating the guiding of the opposite 90 strap.

CHARLES A. PATRICK.
